UNITED STATES PATENT OFFICE.

THOMAS H. DOYLE, OF NORWICH, NEW YORK.

SAFETY-STEP FOR CARS.

SPECIFICATION forming part of Letters Patent No. 258,901, dated June 6, 1882.

Application filed April 11, 1882. (No model.)

To all whom it may concern:

Be it known that I, THOMAS H. DOYLE, of Norwich, in the county of Chenango and State of New York, have invented certain new and useful Improvements in Safety Attachments to Railway-Cars; and I do hereby declare that the following is a full, clear, and exact description of the invention, which will enable others skilled in the art to which it appertains to make and use the same, reference being had to the accompanying drawings, which form a part of this specification.

Figure 1 is a bottom plan view of the end of a railway-car equipped with my improved safety attachment. Fig. 2 is a sectional view on the line *x x*; and Fig. 3 is a sectional view on the line *y y*, Fig. 1.

Corresponding parts in the several figures are denoted by like letters of reference.

This invention relates to an improved safety attachment to railway-cars, which consists essentially in mechanism for automatically turning the steps out of position when the car is in motion, thus preventing any attempt at leaving or boarding the car after starting and the danger resulting therefrom, as will be herein-after fully described, and particularly pointed out in the claims.

In the drawings hereto annexed, A represents the frame of the car-truck, and B is the platform.

C are brackets depending from the ends of the platform, two at each end, so as to form supports for the steps D, said irons or brackets being formed with angles E, as shown, for the purpose stated. The steps D are recessed at their rear corners, as shown at F, so as to fit between the brackets C, and the latter are provided at the vertex of the angles E with eyes G, to receive bolts H, by which the steps D are pivoted to the said brackets.

To the lowermost pivoted step, D, is secured an additional step, I, by means of brackets J, which, when turned down, comes sufficiently near the ground to be easily stepped upon. The rear sides of the pivoted steps D are connected by a rod, K, having an eye, L.

M is a disk firmly secured upon one of the car-axles N, and provided with guide-rods O, projecting from one of its faces, parallel to the axle.

P is another disk, sliding loosely upon the

axle N and guide-rods O, and having arms Q, carrying weights or balls R, pivoted or hinged to diametrically-opposite sides, said arms being connected by pivoted rods S with the sides of disk M, thus forming an ordinary centrifugal governor. The sliding disk P has an annular groove, T, in which is fitted a ring or band, U, which is pivoted between the arms of a forked lever, V, pivoted to a hanger, W, depending from the under side of the car-frame.

X is a rod or shaft journaled longitudinally under the car-frame and provided with a crank, Y, connected by a pivoted rod, Z, with the upper end of the lever. The ends of the shaft X are provided with cranks A', fitted in the eyes L of the rods K, connecting the pivoted steps D at each end of the car. The connecting-rods K of the steps D at opposite ends of the platform are connected by a rod or chain, B', enabling them to be simultaneously operated either by the shaft X or by a lever, C', pivoted to one end of the platform and having one end connected to the rod K. The other end of lever C' may be retained in any position to which it may be adjusted by a segmental ratchet-bar, D'.

From the foregoing description, taken in connection with the drawings hereto annexed, the operation and advantages of my invention will be readily understood. When the car is in motion the governor, mounted upon the axle, operates the shaft X, which, through the rod K, turns the steps to the position shown in dotted lines. When the car stops the steps drop down automatically. By the lever C' the train-men, however, may control the steps, so as to keep them turned up even when the car is stationary.

Having thus described my invention, I claim and desire to secure by Letters Patent of the United States—

1. The combination, with a railway-car, of the brackets C, pivoted steps D, connecting-rod K, a governor mounted upon the car-axle, and mechanism for operating the said pivoted steps automatically by means of said governor, as set forth.

2. The combination of the car-axle, the governor having sliding annularly-grooved disk P, the band U, forked lever V, shaft X, having cranks Y A', connecting-rod Z, brackets C, pivoted steps D, and the connecting-rod K, having eye L, as set forth.

3. The combination of the car-axle, the disk M, having guide-rods O, the sliding disk P, having weighted hinged arms Q, the connecting-rods S, the pivoted steps D, and mechanism, substantially as described, connecting said pivoted steps with the sliding disk P, as set forth.

4. The combination of the brackets C, the pivoted steps D, the connecting-rods K, the rod or chain B', the lever C', and ratchet-bar D', substantially as set forth.

In testimony that I claim the foregoing as my own I have hereto affixed my signature in presence of two witnesses.

THOMAS H. DOYLE.
